(57) **CLAIM**

The ornamental design for a power charger cap, as shown and described.

DESCRIPTION

FIG. 1 is a perspective view of a power charger cap, in accordance my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate portions of the power charger cap and environmental structure that do not form part of the claimed design.
